METHOD AND APPARATUS FOR COATING STRANDS WITH FLOCK

Samuel C. Lilley, Hamden, and Maltby S. Fowler,
New Haven, Conn., assignors to The American
Mills Company, West Haven, Conn., a corporation

Application June 13, 1935, Serial No. 26,356

13 Claims.

(Cl. 91—8)

This invention relates to improvements in methods and apparatus for coating strands with flock, and more particularly to coating elastic strands with flock.

5 One object of this invention is to provide an improved method and apparatus for providing strands with a coating of flock of maximum uniformity and perfection.

10 Another object of this invention is to provide an improved method and apparatus for coating strands with flock at maximum speed and minimum cost.

15 Another object of this invention is to provide improved apparatus for coating strands with flock, the apparatus being of maximum simplicity and durability and of minimum cost.

20 With the above and other objects in view, this invention includes all improvements over the prior art which are disclosed in this application.

25 In the accompanying drawings, in which certain ways of carrying out the invention are shown for illustrative purposes:

Fig. 1 is a schematic sectional elevation of apparatus for coating elastic strands with flock in accordance with this invention;

25 Fig. 2 is an enlarged view similar to Fig. 1, of a small portion thereof;

Fig. 3 is a fragmental, vertical, sectional view on line 3—3 of Fig. 1;

30 Fig. 4 is a horizontal sectional view on line 4—4 of Fig. 3;

Fig. 5 is a vertical sectional view on a reduced scale, on line 5—5 of Fig. 2, with the brush mainly in elevation;

35 Fig. 6 is a horizontal sectional view on a reduced scale, on line 6—6 of Fig. 2;

Fig. 7 is an enlarged horizontal sectional view on line 7—7 of Fig. 1;

40 Fig. 8 is a greatly-enlarged horizontal sectional view through a rubber strand just above the entrance-openings in the bottom of the adhesive-container;

Fig. 9 is a similar view of the rubber strand just above the exit-openings in the top of the adhesive-container, and with a coating of adhesive surrounding the rubber strand;

45 Fig. 10 is a similar view of the rubber strand higher up after a coating of flock has been applied;

50 Fig. 11 is a similar view of the rubber strand still further up after the adhesive coating has flowed to a coating of more uniform thickness;

55 Fig. 12 is a similar view of the rubber strand after the solvents have evaporated out of the adhesive;

Fig. 13 is a vertical sectional view on a reduced scale, on line 13—13 of Fig. 2;

Fig. 14 is a sectional perspective view of a modified form of the invention; and

Fig. 15 is a sectional perspective view of another further modified form of the invention.

In the description and claims, the various parts of the apparatus and steps of the method are identified by specific names for convenience, but they are intended to be as generic in their application as the prior art will permit.

Referring to Figs. 1 to 13 of the drawings, the support 20, which may, for example, be a table, may support the main portion of the mechanism, although it will be obvious that the various parts of the mechanism may be supported by any suitable means.

An adhesive-container or tank 21 (Fig. 2) is secured in an opening 22 in the table 20 by any suitable means, such, for example, as by turn-buttons 23, 24. The tank 21 has a top-plate 25 removably held in place by screws 26, and a bottom-plate 27 removably held by screws 28 which also serve to clamp in place, a gasket 29 of suitable material having a rectangular opening. The top-plate 25 has a top rectangular opening 30 in

which is removably seated a top die-member 31 formed of two parts 32, 33 (Fig. 6) connected by dowel pins 34 secured in one of the die parts, and which dowel pins have a sliding fit in holes in the other of the die parts. The meeting edges of the die parts 32 and 33 have aligned grooves to form holes or openings 35. The bottom-plate 27 has a bottom rectangular opening 36 in which is removably seated a bottom die-member 37 formed of

30 two parts 38, 39, connected by dowel pins (not shown) similar to the dowel pins 34 (Fig. 6) and having aligned grooves to form holes or openings 39. The bottom die 37 has a bordering flange 40 which serves to clamp in place, a gasket 41 of any suitable material having a rectangular opening. The bottom die 37 is removably clamped in place by any suitable means, such as turn-but-

45 tons 42 (Fig. 13).
The flock-applying mechanism is generally designated as 43, and includes two flock-holding chutes 44, 45, at the lower ends of the downwardly-enlarged or flared portions 46, 47 on which are located feeding or feed-regulating brushes 48, 49, 50 rotatably mounted in bearings 50, 51 (Fig. 5), adjustable by screws 52 down and up, toward and from woven-wire or other type screens 53, 54, secured to the removable bottoms 55, 56 respectively of each of the chutes 44, 45.

55 Beneath the chute-bottoms 55, 56 are air-ducts

57, 58. Air-duct 58 extends horizontally and directs air against baffle 59 which latter deflects the air against baffle 60, which latter deflects air against baffle 61. Air-duct 57 extends horizontally part way, then angularly upward and directs air against baffle 62, which latter deflects air against the lower left baffle-portion 63 of the upwardly-extending air-duct 64 which has its opposite sides 65, 66 of undulating form.

10 The upper portion of air-duct 64 has the sides 65, 66 sloped respectively at 67, 68 to provide exits 69, 70 which lead respectively to the chambers 71, 72, which in turn lead to the exhaust-tube or pipe 73, which in turn is connected to a motor-driven, suction or vacuum-producing fan or pump 74, which draws air from pipe 73 and forces it into the porous cloth bag 75 through which the air escapes. The upper rear wall-portion 76 prevents direct passage of air from the air-duct 64 to exhaust-pipe 73, thus compelling the air to move with less violence through the lateral exits 69, 70 and through the chambers 71, 72 to pipe 73. A damper or regulator 77 may be used to provide a convenient way of regulating the degree of suction or volume of air passing through the air-ducts.

30 A drying-chamber, generally designated as 78, preferably has heated-insulated vertical surrounding-walls 79. The drying-chamber 78 may be provided with any suitable heating means, as for example, a bottom-grid 80 having two main openings 81, 82 and a relatively-large number of smaller openings 83, all of which openings extend entirely up through the grid and which openings have continuous walls so as to make a closed inner-chamber 84 in the grid, in which a heating medium such as steam, for example, can be supplied by means of the lead-in and lead-out pipes 85, 86. The two opposite inside walls 81, 82 are of undulating form. A pipe or flue 89 leads from the upper end of the heating-chamber 78 to the outside atmosphere.

40 A roll or drum 88 is pivotally mounted in the upper part of the chamber 78 and is driven by gearing and shaft 81, which in turn is driven by gearing and the vertical shaft 82. Shaft 82, through shaft 83 and gearing, drives the roll 84. A belt 85 connected with the roll 84 or a pulley thereon, serves to drive the roll 88.

45 The vertical shaft 82, through gearing and shaft 87, drives the roll 88. A chain 88 passing over gears 100, 101, 102 serves to drive the feed-brushes 48, 49. The vertical shaft 82 is driven by pulleys and belt 103 from motor 104.

50 The apparatus is adapted to coat any number of strands from one up to eighty or more simultaneously. A supply-reel or reels 105 is mounted to rotate on a shaft or bar 106, and contains strands 107, preferably elastic strands of rubber or the like, and of square, round or other suitable cross-sectional shape. The strands are preferably of a size adapted to be woven or knitted.

55 The multi-toothed, comb-like, strand-separators 108, 109 (Fig. 1) may be pivoted at 110, 111 to be swung into and out of strand-separating position. With the separators 108, 109 swung out of the way, a threading band or cord (not shown) having grip-means on one end, such as a cardboard or fibre strip having properly-spaced strand-gripping slits, adapted to grip the free ends of the strands 107, has its grip-end passed down over the roll 88, through the slot 112 in the top of the duct 64, down through the duct 64, down through the top and bottom openings 35

36 of the tank 21, the tank being empty and the dies 31 and 37 being removed, and down around the roll 88, and has the grip-end connected to the free ends of the strands 107. The grip-end is then passed over the top of the separator 113 and the strands are passed between the teeth of the separator 113, and the threading-band is then drawn upwardly to cause the strands 107 to pass upwardly through the openings 36, 38 of the tank 21, through duct 64, through slot 10 112, through opening 38, between the teeth of separator 108 and 114, around roll 88, between the teeth of separators 109 and 114, around drum 94, between the teeth of separator 115, over drum 96, between the teeth of separator 116, and to a 15 receiving-box 117 having a separate compartment for each strand 107. The threading-band is then disconnected from the strands 107.

20 The two parts of lower die 37 are brought together with the strands 107 in the grooves forming the openings 39 and the die 37 is then secured in place in the bottom of tank 21. The tank 21 is disconnected from the table 20 and lowered therefrom, and the two parts of upper die 31 are brought together with the strands in 25 the grooves forming the openings 35 and the die 31 is then dropped or pushed down in place in the top of tank 21, after which the tank is again secured to the under-side of the table by the turn-buttons 23, 24.

30 Adhesive solution 118 is then poured into the tank 21 through the filler-tube 119 until the adhesive solution is visible in the open end of the tube 119 to bring the general level of the adhesive in the tank 21 to approximately that 35 indicated by the line 120. The open end of the filler-tube 119 thus affords visual means for determining when more adhesive should be added. The adhesive solution may consist of rubber latex, water-dispersed rubber, natural rubber solution, synthetic rubber solution, etc., with or without vulcanizing material, vulcanizing accelerators, fillers, pigment, etc. One adhesive solution which has been found satisfactory consists of approximately twenty per cent rubber, 40 twenty per cent filler, pigment and vulcanizing materials, and the balance volatile rubber solvents.

45 A suitable quantity of fibrous flock 121 formed from material such as cotton, rayon, wool or other 50 suitable fibrous material, is put into the flock-chutes 44, 45.

55 Heat is turned on in the grid 80 and suction-pump 74 and motor 104 are started. This results in the strands 107 being fed upwardly through 55 the bottom die-openings 39, which openings do not need to closely fit the surfaces of the rubber strands as the thickness or viscosity of the adhesive solution prevents leakage down past the strands. As the strands pass up through the adhesive solution 118, they draw the solution up as at 122 and as the strands pass up through the top die-openings 35, a quantity of rubber adhesive solution 123 coats and adheres to the strands 107. As the strands coated with adhesive emerge 60 from the top die-openings 35, flocking starts to occur.

65 The rotating brushes 48, 49 feed flock 121 down through the screens 53, 54 and the air being drawn into the air-ducts 57, 58 carries the particles of flock forward. The flock-charged air-current 124 passing along air-duct 58 strikes and passes around the adhesive-coated strands 107, resulting in flock particles 125 (Figs. 10, 11, 12) sinking more or less deeply into the soft adhesive 75

coating 123 on the strands. As the flock-charged air-current 124 proceeds onward, it strikes the baffle 59, whereupon it is deflected back and again strikes the strands to add more flock particles to the coating on the strands. The flock-charged air-current 124 then strikes baffle 60, whereupon it is deflected back and again strikes the strands to add more flock particles to the coating on the strands. The flock-charged air-current 124 then strikes baffle 61, whereupon it is deflected back and again strikes the strands to add more flock particles to the coating of the strands.

In a similar way to the movement of the flock-charged air-current 124, another flock-charged air-current 126 passes in through air-duct 57 and by alternate deflection by baffles 62 and 63, strikes the strands alternately on opposite sides to add more flock particles to the coating on the strands.

After the two flock-charged air-currents 124 and 126 pass up beyond baffle 61, they merge into a single flock-charged air-current 127, and the undulated sides 65, 66 of the air-duct 64 act as baffles to alternately deflect the upwardly-moving flock-charged air-current 127 back and forth to alternately strike opposite sides of the strands and add more flock particles to the coating on the strands and also absorb the "bleed" of the adhesive through the flock coating. The air-leakage slits 129 permit air to be sucked into the flock-charged air-currents 124, 126 at locations which aid in preventing flock being deposited on the baffles.

As an adhesive-coated portion of a strand passes up away from the top die-member 31, the adhesive coating 123 (Figs. 9, 10) gradually tends to conform to the cross-sectional form of the strand (Fig. 11) and gradually dries until finally it becomes substantially thinner (Fig. 12).

By the time the strands have reached the openings or exits 69, 70 at the top of the air-duct 64, the strands have acquired all the flock that can adhere to them. The flock-charged air-current 127 is prevented by the upper rear wall-portion 16 from directly entering the pipe 13, but is compelled to divide into two oppositely-moving currents which pass through exits 69, 70 with a minimum disturbance of the strands, and through pipe 13 and vacuum-fan 14 into the porous bag 15 where the flock is collected while the air passes out through the pores of the bag 15. It may be found desirable to strike, or have power mechanism strike, the bag 15 at intervals to cause the flock accumulated on the walls to become detached and drop to the bottom of the bag and free the pores to the more free passage of air. The flock which is recovered in bag 15 can be put in the chutes 44, 45 for use over again.

After the strands are fed upwardly through the slot or opening 112 at the top of air-duct 64, they pass up through opening 81 in the heated grid 80, over roll 90, down through grid-opening 82, under roll 94, over roll 96, and into the individual compartments in the box 117. The heated air which passes up through openings 81, 82, 83 is given a back-and-forth motion transversely of the strands by the undulating walls 87, 88 of the drying-chamber 18 to thus more rapidly dry the solvents out of the rubber adhesive, which solvents, in the form of vapor mixed with the air, pass through pipe 89 to the outside atmosphere for safety, as the solvent vapors are likely to be inflammable.

Rolls 98 and 96 may be covered with cotton sheeting to give suitable friction-surfaces, and rolls 90 and 94 may be covered with Holland cloth

curtain material which is glazed and gives a lower degree of coefficient of friction than plain cotton cloth, in order to permit slippage of the rubber strands, if need be. Rolls 90 and 94, instead of being covered with Holland cloth, may be of wood coated with varnish.

Rolls 98, 90 and 94 are so driven that they rotate at the same surface or peripheral speed, thus avoiding substantial stretching of the rubber strands during the flock-applying process. The roll 96 has greater surface speed than roll 94 to keep the strands fairly taut between rolls 94 and 96. Slippage of the strands on roll 96, if it occurs, does no harm.

If, however, it is desired to produce flocked strands of lesser stretch characteristics, then the surface speeds of the various rolls can be driven at such relative speeds as to maintain a desired amount of stretch in the strands while they are being coated and dried.

After the strands 107 have completely unwound off the supply-reel 105 and before the ends have moved up to the bottom die 37, the motor 104 and vacuum-fan 14 are stopped, thus stopping the whole machine. The strands 107 are now cut at 25 a location between the upper roll 90 and the slot 112, and the upper ends of the cut strand-pieces extending up through slot 112 are connected to a threading cardboard carried at the lower end of a band or cord (not shown) for threading over 30 the rolls 90, 94, 96, as previously described. The roll 96 may be rotated by hand or otherwise to bring the remainder of the strands above the cut, into the compartments of the box 117.

The cork or plug 128 (Fig. 13) is removed from tank 21 to empty the tank of adhesive, and the tank is then released from table 20 by means of the turn-buttons 23, 24, whereupon the tank 21 is lowered to result in the lower ends of the cut strand-pieces passing up through the dies 37, 31. 40 A second adhesive tank like tank 21, and empty of adhesive, but with strands from a new supply-reel threaded up through both the bottom and top dies of the second tank is now brought to a position adjacent the lower ends of the cut strand-pieces hanging down below table 20. The upper ends of the new strands and the lower ends of the corresponding cut strand-pieces are respectively tied together, and the threading cardboard is then pulled over the rolls 90, 94, 96 until the new 50 upper strand-ends reach a second box 117, the first box 117 with flocked strands having been removed for placing in the vulcanizer. The second tank is now secured to the table 20 by the turn-buttons 23, 24 and is then filled through 55 tube 119 to the proper level with adhesive solution, ready for flocking the second set of strands in the manner previously fully described.

While the strands are being flocked, quantities of flock can be added from time to time to the 60 chutes 44, 45, and although the lower portions of the chutes are downwardly flared or enlarged to minimize any tendency to "clock" or "bridge over" the brushes, nevertheless, on account of the light, fibrous nature of the flock, it is preferable not to 65 put too much flock in the chutes at any one time, but instead, to add small quantities at more frequent intervals.

Instead of using the bag 15, the upper ends of flock-chutes 44, 45 may each be provided with an 70 extension provided with a pair of sliding or pivoted shut-offs or dampers, and each extension may have a porous bag connected to it, both bags being connected to one or two vacuum-fans as desired. The dampers of each pair are arranged 75

one above the other and may be interconnected by mechanism so that as soon as one is completely closed, the other opens. They may be actuated by hand or by power-driven mechanism. Also, if desired, mechanism may be provided, either hand or power-actuated, for striking the bags to loosen the flock from the walls thereof, at intervals. Thus, by the successive actuation of the two dampers of each pair, when the upper damper is first opened, the flock accumulated thereon is dropped onto the closed lower damper, then the upper damper is closed to shut off the air-pressure from the lower damper and the latter is opened to drop the flock into the chute below it, whereupon the lower damper is again closed. This cycle being repeated at any desired intervals. Inasmuch as only a very small percentage of flock from the flock-charged air adheres to the strands, it will only be necessary to occasionally add new flock to the flock-chutes, which can be done through normally-closed openings provided in the sides of the flock-chutes.

In the form of the invention illustrated in Fig. 14, strands 107 to be flock-coated, extend vertically up through the adhesive-tank 21 and up through a baffled air-duct 130. Entering the air-duct 130 in opposite directions, are air-ducts 131, 132 which respectively lead from spray-guns 133, 134. Free-air openings 133a and 134a are provided at each side of the spray-guns 133 and 134. Each spray-gun has a flock-supply tube 135 and a compressed-air-supply tube 136 by which flock-charged air is fed under pressure into and through the air-ducts 131, 132 to coat the strands with flock in a manner similar to that described concerning Figs. 1 to 13. The remainder of the apparatus can be similar to that shown in Figs. 1 to 13. If desired, vacuum or suction apparatus, such, for example, as 13, 74, 75 of Fig. 1, may be used in conjunction with the pressure spray-guns of Fig. 14.

In the form of the invention illustrated in Fig. 15, strands 107 to be flock-coated, extend vertically up through a horizontally-extending air-duct 140 of baffled or undulating form. Spray-guns 141 each have a flock-supply tube 142 and a compressed-air-supply tube 143 by which flock-charged air is fed under pressure into and horizontally through the air-duct 140 and out the exit-opening 144. The flock-charged air coats the strands with flock in a manner similar to that described concerning Figs. 1 to 13. The remainder of the apparatus can be similar to that shown in Figs. 1 to 13. If desired, vacuum or suction apparatus, such, for example, as 13, 74, 75 of Fig. 1, may be used in conjunction with the pressure spray-guns of Fig. 15.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

We claim:

1. The method of coating a strand with flock, including: rendering the surface of a strand adhesive; feeding the strand approximately axially of itself; and causing two currents of flock-charged air to surround and move in opposite directions to one another across the axially-moving strand.

2. The method of coating an elastic strand

with flock, including: stretching an elastic strand; rendering the surface of the strand adhesive; and applying flock to the adhesive surface of the strand while stretched by causing two currents of flock-charged air to surround and move in opposite directions to one another across the strand.

3. The method of coating a strand with flock, including: applying a coating of liquid adhesive to the surface of the strand; feeding the strand approximately vertically axially of itself; and applying flock to said coating of adhesive by means of a suction-produced current of flock-charged air caused to move back and forth across said strand.

4. Apparatus for coating a strand with flock, including: means for feeding a strand approximately axially of itself during a portion of its travel; means for rendering the surface of the axially-moving portion of the strand adhesive; and means for charging a current of air with flock and causing said current of flock-charged air to surround and move back and forth across the axially-moving portion of the strand.

5. Apparatus for coating a strand with flock, including: means for feeding a strand approximately axially of itself during a portion of its travel; means for rendering the surface of the axially-moving portion of the strand adhesive; and means for charging two currents of air with flock and causing said currents of flock-charged air to surround and move in opposite directions across the axially-moving portion of the strand.

6. Apparatus for coating a strand with flock, including: means for feeding a strand approximately vertically axially of itself during a portion of its travel; means for coating the surface of the axially-moving portion of the strand with adhesive liquid; and means for charging two oppositely-directed currents of air with flock and causing said currents of flock-charged air to surround and move back and forth across the axially-moving portion of the strand.

7. Apparatus for coating a strand with flock, including: means for feeding a strand approximately vertically axially of itself during a portion of its travel; means for coating the surface of the axially-moving portion of the strand with adhesive liquid; and means for charging a current of flock-charged air to surround and move back and forth repeatedly across the axially-moving portion of the strand by means of reflecting surfaces located adjacent and at opposite sides of the strand.

8. Apparatus for coating a strand with flock, including: means for feeding a strand approximately axially of itself during a portion of its travel; means for rendering the surface of the axially-moving portion of the strand adhesive; and means including a baffle-chamber of undulating form, the undulations of which are spaced from the strand, for charging air with flock and causing said flock-charged air to surround and move back and forth across the axially-moving portion of the strand.

9. Apparatus for coating one or more strands with flock, including: a container for liquid adhesive; a baffle-chamber adjacent said adhesive-container; means for feeding one or more strands through adhesive in said adhesive-container and approximately axially of itself through said baffle-chamber; and means for charging air with flock and causing said flock-charged air to move through said baffle-chamber; said baffle-chamber

having baffle walls on opposite sides of and spaced from the strands and being adapted to cause said flock-charged air to surround and move back and forth across the axially-moving portion of the strands.

5 10. Apparatus for coating one or more strands with flock, including: a container for liquid adhesive; a baffle-chamber adjacent said adhesive-container; means for feeding one or more strands through said adhesive-container and approximately vertically axially of itself through said baffle-chamber; and means for charging air with flock and causing said flock-charged air to move through said baffle-chamber; said baffle-chamber

10 15 having baffle walls on opposite sides of and spaced from the strands and being adapted to cause said flock-charged air to surround and move back and forth repeatedly across the axially-moving portion of the strands.

20 11. Apparatus for coating one or more strands with flock, including: a container for liquid adhesive; a baffle-chamber adjacent said adhesive-container; means for feeding one or more strands through adhesive in said adhesive-container and approximately axially of itself through said baffle-chamber; and means including suction-means for charging air with flock and causing said flock-charged air to move through said baffle-chamber; said baffle-chamber having baffle walls on opposite

25 30 sides of and spaced from the strands and being adapted to cause said flock-charged air to surround and move back and forth across the axially-moving portion of the strands.

12. Apparatus for coating one or more strands with flock, including: a container for liquid adhesive; a baffle-chamber adjacent said adhesive-container; means for feeding one or more strands through adhesive in said adhesive-container and approximately axially of itself through said baffle-chamber; and means including suction-means and flock-regulating-and-feeding means for charging air with flock and causing said flock-charged air to move through said baffle-chamber; said baffle-chamber having baffle walls on opposite sides of and spaced from the strands and being adapted to cause said flock-charged air to surround and move back and forth across the axially-moving portion of the strands.

15 20 25 30 13. Apparatus for coating a plurality of strands with flock, including: a container for liquid adhesive and having a row of exit die-openings for the passage of a row of strands to be coated and each opening surrounding and of substantially larger diameter than a strand; means for feeding a row of strands through adhesive in said adhesive-container and approximately vertically axially of the strands through said row of exit openings, whereby a coating of liquid adhesive adheres to 25 and surrounds the strands; and means for charging air with flock and causing the flock-charged air to move back and forth transversely of and across the row of strands.

SAMUEL C. LILLEY.
